United States Patent Office

Des. 209,742
Patented Jan. 2, 1968

209,742

CHAIR

Alan G. Gass, 602 S. Harrison Lane,
Denver, Colo. 80209

Filed Mar. 17, 1966, Ser. No. 1,510

Term of patent 7 years

(Cl. D15—1)

FIG. 1

FIG. 2

FIG. 3

FIG. 4

FIG. 5

FIGURE 4 is a rear view in elevation of the chair of the present invention; and

I claim:

The ornamental design for a chair, as shown.
